UNITED STATES PATENT OFFICE.

GUST GRAFFINBERGER, OF PORTLAND, OREGON.

TRIMMER-SAW MECHANISM.

Application filed November 3, 1924. Serial No. 747,556.

My invention relates to means for controlling, from a central station, the operations of pressure cylinders of the type illustrated in my Letters Patent of the United States granted May 12, 1925, No. 1,537,437, entitled trimmer saw mechanism.

Where pressure cylinders are used admitting the fluid at each end, a valve control for such cylinder is, of course, required which will function to move the valve-operating lever uniformly in both directions, in order that said pressure cylinders may be operated to attain the results pointed out in my said preceding patent. In short, the control of the cylinders' valves from the central station, must be just as effective as if the operator had direct manual control of the valve lever.

Such mode of operation, in my opinion may only be practically attained by the employment of stiff connecting rods, between the valves of the cylinders and the control devices located at the central station, so that the push and the pull motions transmitted to the valve lever will be uniform, and insure the operation of the valve control equally positive in either direction.

It further requires that a proper amount of motion be transmitted by the key or lever of the control devices, at the central station, to the levers of the valves of the respective cylinders, in order to assure the proper operation of the valves. Therefore, either the movement of the valve levers of the respective cylinders must be adjusted to the amount of motion transmitted to them, respectively, by the related lever or key at the central station, or a uniform amount of motion must be transmitted to the valve levers of all cylinders.

I find it convenient to graduate the length of stroke of the lever of said control mechanism, so as to impart a uniform amount of motion to the valve lever of each cylinder.

The necessity of such graduation is diagrammatically illustrated by Fig. 9 of the accompanying drawings. Let 32^x of said diagrammatic figure represent one link of the control mechanism at the central station, and the distance from *a* to *b* represent the required movement of the valve of the cylinder 14^x. Let 14^y represent another cylinder whose valve must be given the same amount of motion as the valve of the cylinder 14^x. Since the line of motion of the

link of said control mechanism makes a straight angle with the line of motion of the valve of the cylinder 14^x, such link need only be moved the distance from *a'* to *b'*; but where said lines of motion make a different angle with each other, allowance must be made for the angle at which they diverge from each other. Thus the greater the divergence, the longer must be the stroke of the related link of the control mechanism in order to impart a uniform amount of motion to the valve levers of all the cylinders. Hence, where for example, a cylinder is located as at 14^y, in order to move the valve lever thereof the distance from *a* to *b* it will be necessary to move the link 32^y of the control mechanism the distance from *a'* to *b'*.

It is further essential that the operating means included in the valve control of said cylinders thus specifically referring to the fulcruming of the operating levers—be so arranged as to reduce the amount of power required to operate said valve to a practical minimum. Because if the valve control works stiff it would tend to impose too much resistance to its operation, and hence would tend to flex the connecting stiff rods between the levers, or keys, of the control station, and the valve-lever to such extent as to render the operation of the valve control unreliable; and it would be impractical to use heavy stiff rods for said connections.

The object of my invention, therefore, is to provide dependable operating connections between the control devices at the central stations and the valve-levers of the respective pressure cylinders so that the operation of the latter will be effectively controlled as mentioned.

I attain my object by providing for the operation of the valve control of said pressure cylinders, a series of short stiff rods or links reciprocated in bearings restraining the lateral deflection thereof, and connecting such stiff rods through the medium of other stiff rods with the operating means, that is, the levers of said valve control, and providing means for operating said short rods individually, and adapted to graduate the stroke length of said short rods, respectively, relatively to the variations in the angles of divergence of the points at which particular cylinders are located from the line of motion of the related short rod, so as to trans-

mit uniform operative motion to all the valve lever controls of all the cylinders.

A further object of my invention is to provide simple devices by which the operation of the individual units of the bank of cylinders may be reliably accomplished, as mentioned.

Further details of construction and of the practical use of my invention are herein after described with reference to said accompanying drawings, of which the other figures represent as follows:

Fig. 1 is a fragmentary plan view of a series or bank of trimmer saws taken on the line 1—1 of Fig. 2, and illustrates the practical application of my invention for controlling the operation of the valves of the pressure cylinders of said series;

Fig. 2 is a side elevation of one of the saw units, its operating pressure cylinder and the means embodied in my invention for controlling the valve of the latter;

Fig. 2^a is a diagrammatic view illustrating a detail of construction in the saw-frames; described in the body of the specification;

Fig. 3 is a fragmentary perspective view of one key or lever of the control mechanism provided at the central station, and illustrates the arrangement of the means provided by me for graduating the strokes of the levers of said mechanism so as to transmit uniform and sufficient motion to the valve levers of the cylinders; also illustrates the means provided by me for holding said levers in one position until moved into another;

Fig. 4 is a fragmentary front elevation of a portion of the keyboard of the control mechanism of said trimmer-saws;

Fig. 5 is a larger scale fragmentary side elevation of the devices shown in Fig. 2, portions of the cylinder and the keyboard being shown in section to disclose details of construction;

Fig. 6 is a front elevation of the pressure cylinder unit shown in Fig. 5; and

Figs. 7 and 8 are fragmentary views of the adjustable rigid knuckle by which one rod element is connected to the other, so as to eliminate play.

Fig. 9 is a diagrammatic plan view illustrating the operation of the valve rods and levers.

My invention is illustrated as being embodied in an overhead trimmer saw mechanism, in which a number of saw units 1, carried by swinging frames 2, are driven by belts 3 mounted over the saw belt pulleys 4 and the driving pulleys 5. Each saw pulley 4 is fixed to a saw arbor 6 and the driven pulleys 5 are mounted on a common driving shaft 7 carried by bearings 8 which are fastened to timbers 9 of the mill structure. The swinging saw frames 2 are carried upon pivot pins 10 in the hangers 11 which are

mounted upon a common shaft 12. Said shaft 12 is carried by supports 13 fastened to the timbers 9 of the mill structure.

I provide an adjustable means for setting said hangers 11 on said shaft one type of such adjustable means being shown as comprising the set screw 11^a. By rotating said hangers relatively upon said shaft 12, the axis about which said swinging frame 2 rotates is adjusted, as is shown diagrammatically in Fig. 2^a.

The cylinders 14 which act as the actuating means for moving said saw frames 1 into and out of operative position, are preferably double acting as illustrated in Fig. 5. That is, said cylinders have inlet and outlet ports 15 and 16 respectively at one end and similar ports 15^a and 16^a at the other. The outlet ports 16 and 16^a are spaced a substantial distance from the ends 17 and 17^a of said cylinder, thus to entrap a substantial quantity of the actuating fluid, which might be either compressed air or steam, said trapped actuating fluid thus serving as a cushion for the piston 18 at the ends 90 of its travel in either direction.

I provide a valve element 19 which is preferably of the type illustrated in my application for a patent Serial No. 616,322 which was filed first day of February 1923. Said valve element is provided with dual control mechanism 19^a and 19^b respectively, one-half thereof controlling the upper portion and the other half the lower end, of said cylinder, as shown in Fig. 5. Both halves of said valve element receive actuating fluid through a common inlet 19^c but control the admission and emission of said actuating fluid thru separate outlet pipes 19^d and 19^e to and from said upper and lower ends of said pressure cylinder, respectively. Each valve element is controlled by a lever 20 which is pivoted at 20^a, between said halves, said lever thus being arranged so that when one half of the valve element is actuated to admit steam to its respective end of the cylinder, the other valve half is actuated to release the steam from the other end, through the auxiliary outlet 19^f, common to both halves of said valve element. The common lever 20 thus actuates the halves of said valve element in time with each other, so that the piston is driven in one direction by the pressure of steam behind it and the pressure of steam on the opposite side of said piston is relieved simultaneously to permit said piston to be so driven. Said lever 20 has a relatively great mechanical advantage as is evident in Fig. 5, the portion of said lever extending from said pivot 20^a to the pivot pin 30^c by which the stiff rod 30 is connected to said lever greatly exceeding the distance from said pivot to the connections 20^d and 20^e by which the valve halves 19^a and 19^b are connected re-

spectively to said lever 20. The relatively great mechanical advantage of said valve operating lever 20 permits a relatively slight pressure of the stiff rods 30 to actuate said valves. The control lever 20 has an elongated portion 20^b provided with a forked end 20^c which straddles a control rod 21 which actuates the mechanical catch 22 pivotally mounted in a hanger 23 carried by the pressure cylinder 14. Such mechanical catch resembles a bell crank and is pivotally mounted upon a pin 23^a in said hanger 23. As is shown in Figs. 5 and 6 when said rod 21 is lowered the portion 22^a of said mechanical catch is rocked clock-wise out of the path of the flange 24 upon the piston rod 25 of the piston 18 and when said rod is raised said portion 22^a is rotated counter-clockwise to extend across the path of said flange to engage the latter, said catch 22 engaging the hanger 23 to prevent further movement.

The end 25^a of said piston rod 25 is bifurcated and straddles the end of a connecting rod 26, the end 26^a of the latter and the end 25^a of said piston rod being pivotally connected by a bolt 26^b. The opposite end 26^c of said connecting rod 26 is bifurcated, as shown in Fig. 6, and is mounted between two spaced upright ears 27 carried by the swinging saw frame 2 and is fastened therein by a pivot pin 27^a. Said connecting rod 26 is pivotally mounted at each end to accommodate the swinging of the saw frame.

Each valve operating lever 20 is connected to one operating key 28 of the bank of keys which constitute the selective control 29. Each of said keys 28 is connected with its respective control lever 20 through an extensible relatively stiff member. A hollow rod or tube 30 which is made in sections which overlap as shown in Fig. 2 and which are connected by an adjustable coupling 31 provided with a set screw 31^a for holding the coupling and the overlapped ends in set position. The end 30^a of said rod 30 fastened to the control lever 20 is preferably bifurcated and straddles the end of said lever, said connection being made through a pivot pin 30^c, and the opposite end 30^b is also bifurcated and straddles the end of a slidable reciprocating connecting link 32. The joint or knuckle between said link 32 and the rod 30 is made through a releasable tightening screw 33 which is threaded into one portion of the rod end 30^b and also into that end of the link 32 so that a knuckle is formed which can be screwed tight to hold the parts in set position. As shown in Figs. 7 and 8 the connection between said link 32 and the end 30^b of the rod 30 may be angular as shown in dotted lines when the connections are made to hold the saws in saws up position, said adjusting screws are tightened in place and when it is desired to actu-

ate the saws, said connection will not slip angularly but will transmit the thrust of the key 28 through the link 32 and the rod 30 to the valve operating lever 20.

I preferably provide an adjustable connection 34 between the key 28 and the link 32 so that the length of travel given the link 32 can be varied. As shown in Fig. 3 the end 32^b of said link is slotted and the adjustable connection 34 is pivotally mounted therein upon the pin 35. The adjustable connection 34 is connected to the key 28 through one of a series of holes 28^b made in the lower end 28^a of said key.

As is shown in Fig. 1 the stiff rod for operating the valves of the pressure cylinders extend in a fan-shape from the keyboard 29, the rods connected to the valve levers of the pressure cylinders directly in front of the operators cage being substantially alined with their links 32 while the rods connected to the valves of the other pressure cylinders make a substantial angle with their links.

The paths described by the valve levers of the pressure cylinders are always in substantial alinement with that of their rods 30, while the paths of the links are in substantial parallelism with each other. It is necessary therefore that an angular joint or knuckle connect the ends of the links to the ends of the rods.

In Fig. 9, I show diagrammatically the paths of travel of one end link with its rod and valve lever, as compared with the travel of the similar parts for one of the middle pressure cylinders. When the link 32^x for one of the middle pressure cylinders 14^x is thrust forwardly by its key, it will move its rod 30 an equal distance, because it is alined therewith. For example, referring to said figure, if it is necessary to move the valve operating lever 20, a unit distance $a-b$, it is but necessary to shift said link 32^x an equal distance $a'-b'$ for the middle cylinders, in which the link 32^x and connection 30 are in substantial alinement. To produce travel $a-b$ in the valve operating lever 20 for an end cylinder 14^y the link 32^y must be moved a greater distance $a'-b'$.

Inasmuch as the paths of travel of the links 32 are fixed in parallel planes and the paths of travel of the valve levers are fixed in more or less angular planes, it is necessary for said rods 30 to flex laterally in transmitting the thrust from a link to a lever or else it is necessary that said connections pivot about their knuckle-joints with their associated links. I preferably form said knuckle-like joint as a fixed connection, as has been brought out heretofore, and thus eliminate possible play in said connection. Said rods 30 in transmitting a thrust to the valve operating levers 20 of the end cylinders must thus be flexed to describe a curved path until the said end rods are flexed later-

ally to assume the position shown diagrammatically in said Fig. A. This difference in travel is taken care of by the making of the adjustable connection through the holes 28^b. 5 The connection for the middle saws is made through the uppermost of the holes 28^b that is, the hole closest to the pivot shaft 36 for said key, and the hole at the extremity of 10 said key, or furthest away from the pivot shaft 36 is used for making the connection to the end saws. The keys 28 for all of the saws are mounted upon the key pivot shaft 36 which is supported by the sides of the casing 37 which houses the keys and the remainder of the control mechanism, this being 15 shown in Fig. 4. Said casing also provides spaced supports 37^a for the reciprocated links 32, as shown in Fig. 5. These supports 37^a are spaced a sufficient distance 20 apart so that the thrust of the links 32 against the angularly arranged rods 30 will not tend to flex said links and cause them to bind relatively in said supports.

I also preferably provide a shaft 38 which 25 extends across said casing and is supported by its sides, said shaft carrying a plurality of spaced actuating arms 39 held to said shaft by set screws 40. Said shaft 38 is provided with an operating handle 41 and by 30 moving said handle and thus the shaft 38 and the arms 39 in one direction said arms 39 engage certain of said keys to move the saws controlled by said selected keys from inoperative to operative position. This feature 35 however is common in control mechanisms of this character at the present time. I also mount on the pivot shaft 36 operating arms 42 which are connected by a clearing rod 43 which extends across all of the keys and is adapted to engage any of the 40 keys which are holding their respective saws in operative position, and to move said keys to the position in which they will arrange their saws in inoperative position, this feature 45 also being common in trimmer saw control mechanisms at the present time.

I preferably provide each of said keys with a spring which tends to hold the key either in operative or inoperative position, 50 or at the half way mark between said two positions. I attain this by providing a protuberance 44 upon the hub 28^c of each key, said protuberance on said hub preferably being integral therewith. I mount a bifurcated member 45 over each protuberance connecting the same by a pivot pin 46. Each bifurcated member 45 is longitudinally slidable upon a pin 47 mounted upon a common shaft 48 which extends across the casing 37 and which 55 is supported by the sides thereof. I preferably mount a coil spring 49 about each of said pins 47, said coil spring bearing against the bifurcated member 45 at one end and against the hub 47^a of the pin at the other. 60 The protuberance 44 is arranged angularly

on the hub 28^c for said key, the degree of angularity being such that the protuberance 44 will be in exact alignment with the pin 47 when said key is arranged at the half way mark. And thus except when said key is arranged carefully at the halfway mark the coil spring 49 will tend to move the key into operative or inoperative position depending upon its position relatively to the half way mark. Said spring 49 is preferably of such strength that it will not exercise a substantial force upon said key which would prevent the key from being manually held in a predetermined position. The strength of said spring is merely sufficient to prevent the key 70 from being moved out of operative or inoperative positions by an inadvertent jar or by the vibration of the mill structure. 75

As is common practice said control mechanism 29, which is composed of a bank of keys 28 and the other mechanism connected therewith which has hereinbefore been referred to, is mounted in an operator's cage 53 supported by timbers of the mill structure, which cage is arranged above the conveyor 50 which moves the boards 51 to be cut along the feed table 52 and under the trimmer saws. 80

The operator's cage 53 is arranged so that the operator has an unobstructed view of the 90 boards 51 being moved along by said conveyors and the rods 30 are of such size as not unduly to obstruct the vision of said operator. 95

The operation of my device is as follows: 100

When the saws are in "saws up" position as shown in full lines in Fig. 2, the boards 51 can pass beneath said saws. When any of the saws are in saws down position shown in dotted lines, however, said saws cut the 105 board. As shown in Fig. 1, the saws are equally spaced along the conveyor for said board and thus the saws when lowered to operative position cut the board at predetermined intervals. Saws in "saws up" position are lowered in the following manner referring to Fig. 2: 110

The key 28^c is pivotally connected to the link 32^c by the connection 34^c and said link reciprocates the relatively stiff rod 30^c to move the operating lever 20 for the valve element 19. When the key 28^c is moved to the angular position assumed at the present time by the key 28^b, it will cause the saw to be lowered to operative or "saws down" position. When the key is thus moved it exercises a compressive thrust upon the connection 34^c, the link 32^c, and the relatively stiff rod 30^c. The rod 30^c being relatively stiff can transmit the movement of said key, in 120 either direction, directly to the operating lever 20 for said valve 19. 125

As an auxiliary safety device I provide the mechanical catch 22 for holding the saws in "saws up" position and I pro- 130

vide said mechanical catch with operating means consisting of the control rod 21 provided with adjustable nuts 21^a carrying a spring 21^b between them. Said 5 means are actuated by the movement of said operating lever 20 so that when said lever arranges said valve, to permit the actuating fluid to lift the piston in the cylinder the mechanical catch is thrown into engaging 10 position relatively to the flange 24 on the piston rod. This flange 24 has a tapered periphery and the underside of the extremity of the portion 22^a of said mechanical catch is beveled so that when said flange moves 15 upwardly it is free to pass by the mechanical catch. Said flange merely lifts said catch slightly and compresses the spring 21^b shown in Fig. 5, and after passing beyond said portion 22^a the spring 21^b returns said catch portion 22^a to horizontal position in which position said flange can not pass downwardly 20 beyond the latter subsequently until the catch is moved by the actuation of the valve operating lever 20.

25 I claim:

1. In trimmer saw mechanism comprising a fluid pressure cylinder for each saw in which the fluid is admitted at each end, a valve control for such cylinder, and operating means, included in said valve control, arranged to reduce the amount of power required to operate said valve control to a practical minimum, means located at a central station for operating said valve controls, comprising a series of parallel short stiff rods, fixed guide bearings for such rods adapted to restrain the lateral deflection, other stiff rods connecting said short rods with said valve operating means, respectively, means for operating said short rods individually, adapted to graduate to the length of stroke thereof, respectively, relatively to the variations in the angles of divergence of the points at which particular cylinders are located from the line of motion of the related short rod, so as to transmit uniform operative motion to all of said valve operating means.

2. In trimmer saw mechanism comprising a fluid pressure cylinder for each saw in which the fluid is admitted at each end, a valve control for such cylinder, and an operating lever, included in said valve control, fulcrumed to reduce the amount of power required to operate said valve control to a practical minimum, means located at a central station for operating said valve controls, comprising a series of parallel short stiff rods, fixed guide bearings for such rods adapted to restrain the lateral deflection, other stiff rods connecting said short rods with said valve operating levers, respectively, means for operating said short rods individually, adapted to graduate to the length of stroke thereof, respectively, relatively to

the variations in the angles of divergence of the points at which particular cylinders are located from the line of motion of the related short rod, so as to transmit uniform operative motion to all of said valve operating means.

3. In trimmer saw mechanism comprising a fluid pressure cylinder for each saw in which the fluid is admitted at each end, a valve control for such cylinder, and operating means, included in said valve control, arranged to reduce the amount of power required to operate said valve control to a practical minimum, means located at a central station for operating said valve controls, comprising a series of parallel short stiff rods, fixed guide bearings for such rods adapted to restrain the lateral deflection, other stiff rods connecting said short rods with said valve operating means, respectively, means for operating said short rods individually, and said means comprising a lever for each rod, the fulcrums of all levers being uniformly arranged, and means for graduating the length of stroke transmitted by the latter levers to said short rods, respectively, relatively to the variations in the angles of divergence of the points at which particular cylinders are located from the line of motion of the related short rod.

4. In trimmer saw mechanism comprising a fluid pressure cylinder for each saw in which the fluid is admitted at each end, a valve control for such cylinder, and an operating lever, included in said valve control, fulcrumed to reduce the amount of power required to operate said valve control to a practical minimum, means located at a central station for operating said valve controls, comprising a series of parallel short stiff rods, fixed guide bearings for such rods adapted to restrain the lateral deflections, other stiff rods connecting said short rods with said valve operating levers, respectively, means for operating said short rods individually, and said means comprising a lever for each rod, the fulcrums of all levers being uniformly arranged, and means for graduating the length of stroke transmitted by the latter levers to said short rods, respectively, relatively to the variations in the angles of divergence of the points at which particular cylinders are located from the line of motion of the related short rod.

5. In trimmer saw mechanism comprising a fluid pressure cylinder for each saw in which the fluid is admitted at each end, a valve control for such cylinder, and operating means, included in said valve control, arranged to reduce the amount of power required to operate said valve control to a practical minimum, means located at a central station for operating said valve controls, comprising a series of parallel short stiff rods, fixed guide bearings for such rods

adapted to restrain the lateral deflection, other stiff rods connecting said short rods with said valve operating means, respectively, means for operating said short rods individually, said means comprising a lever for each rod, the fulcrums of all levers being uniformly arranged, and means for graduating the length of stroke transmitted by the latter levers to said short rods, respectively, relatively to the variations in the angles of divergence of the points at which particular cylinders are located from the line of motion of the related short rod, and means for holding said levers of the central station in one position until moved to another.

6. Operating mechanism for the valves of a bank of pressure cylinders of the character described, comprising a guide-block, a series of short stiff rods bearing in said guide-block and thereby restrained against lateral deflection, auxiliary stiff rods for connecting said short rods with the valves of said cylinders, respectively, means for rigidly connecting said auxiliary rods to said short rods and at a variable angle therewith, means for operating said short rods individually, and adapted to graduate the length of their strokes, and relatively to the variations in the angles of divergence of the points at which particular cylinders of said bank are located from the line of motion of that short rod with which it is connected.

7. Operating mechanism for the valves of a bank of pressure cylinders of the character described, comprising a guide-block, a series of short stiff rods bearing in said guide-blocks and thereby restrained against lateral deflection, auxiliary stiff rods for connecting said short rods with the valves of said cylinders, respectively, said auxiliary rods being adjustable in length, means for rigidly connecting said auxiliary rods to said short rods and at a variable angle therewith, means for operating said short rods individually, and adapted to graduate the length of their strokes, and relatively to the variations in the angles of divergence of the points at which particular cylinders of said bank are located from the line of motion of that short rod with which it is connected.

8. Operating mechanism for the valves of a bank of pressure cylinders of the character described, comprising a guide-block, a series of short stiff rods bearing in said guide-block and thereby restrained against lateral deflection, auxiliary stiff rods for connecting said short rods with the valves of said cyl-

inders, respectively, means for rigidly connecting said auxiliary rods to said short rods and at a variable angle therewith, a series of operating levers of the first class, having their fulcrums uniformly arranged, and links connecting said levers with said short rods, said links being adjustable to graduate the length of stroke of said short rods, and relatively to the variations in the angles of divergence to the points at which particular cylinders of said bank are located from the line of motion of that short rod with which it is connected.

9. Operating mechanism for the valves of a bank of pressure cylinders of the character described, comprising a guide-block, a series of short stiff rods bearing in said guide-block and thereby restrained against lateral deflection, auxiliary stiff rods for connecting said short rods with the valves of said cylinders, respectively, said auxiliary rods being adjustable in length, means for rigidly connecting said auxiliary rods to said short rods and at a variable angle therewith, a series of operating levers of the first class, having their fulcrums uniformly arranged, and links connecting said levers with said short rods, said links being adjustable to graduate the length of stroke of said short rods, and relatively to the variations in the angles of divergence of the points at which particular cylinders of said bank are located from the line of motion of that short rod with which it is connected.

10. Operating mechanism for the valves of a bank of pressure cylinders of the character described, comprising a guide-block, a series of short stiff rods bearing in said guide-block and thereby restrained against lateral deflection, auxiliary stiff rods for connecting said short rods with the valves of said cylinders, respectively, means for rigidly connecting said auxiliary rods to said short rods and at a variable angle therewith, a series of operating levers of the first class, having their fulcrums uniformly arranged, and links connecting said levers with said short rods, said links being adjustable to graduate the length of stroke of said short rods, relatively to the variations in the angles of divergence of the points at which particular cylinders of said bank are located from the line of motion of that short rod with which it is connected, and means for holding said levers of the central station in one position until moved to another.

GUST GRAFFINBERGER.
